(57) **CLAIM**

The ornamental design for a portable cinema case, as shown and described.

DESCRIPTION

FIG. 1 is a front perspective view of a portable cinema case according to the present invention.

FIG. 2 is a rear perspective view of the portable cinema case of FIG. 1.

FIG. 3 is a front view of the portable cinema case of FIG. 1.

FIG. 4 is a rear view of the portable cinema case of FIG. 1.

FIG. 5 is a left side view of the portable cinema case of FIG. 1.

FIG. 6 is an right side view of the portable cinema case of FIG. 1; and,

FIG. 7 is a top view of the portable cinema case of FIG. 1. No bottom view is shown, as no claim is made to the design of the bottom of the portable cinema case.

The broken lines illustrate portions of the portable cinema case and form no part of the claimed design.

1 Claim, 7 Drawing Sheets
